UNITED STATES PATENT OFFICE.

WINFIELD SCOTT GETCHELL, OF OAKLAND, CALIFORNIA.

SAFETY SIGHT-FEED REFLECTOR.

SPECIFICATION forming part of Letters Patent No. 363,060, dated May 17, 1887.

Application filed January 20, 1887. Serial No. 224,945. (No model.)

To all whom it may concern:

Be it known that I, WINFIELD SCOTT GETCHELL, of the city of Oakland, county of Alameda, and State of California, have invented an Improvement in Safety Sight-Feed Reflectors; and I hereby declare the following to be a full, clear, and exact description thereof.

My invention relates to improvements in those devices which have what are known as "sight-glasses," for the purpose of watching their operation; and my invention consists, in connection with the sight-glass, of a guard or shield between the observer and the glass and a reflecting-surface or mirror on the other side of the glass, whereby, though said glass is concealed from direct vision, its operation may be as readily observed in the reflecting-surface or mirror.

My invention further consists in the particular and novel arrangement and combination of said guard and mirror and their relation to the sight-glass, all of which I shall hereinafter fully describe.

The object of my invention is to protect the observer from injury due to the bursting of the sight-glass.

Though my invention is applicable to all devices which have sight-glasses the contents of which are under such pressure or are of such a nature as to tend to burst the glass, I shall confine my description and illustration to what are known as "sight-feed lubricators," which are placed in locomotive-cabs on the boiler-head, and which feed oil to the cylinders and valves.

Referring to the accompanying drawings, Figure 1 is a perspective view of my safety mirror-sight, showing its application to a sight-feed lubricator, one-half only of which is shown, as it is alike on both sides. Fig. 2 is a plan of the guard and mirror, showing their connection.

A is here used to designate the lubricator as a whole. Its various parts need not be more particularly described than to say that B is the sight-glass on one side. This glass is, as usual, filled with the water of condensation, which is under considerable pressure, and through this water the drop of oil ascends at required intervals.

The lubricator is attached to the boiler-head

in a position to be observed constantly by the engineer, the sight-glass on one side furnishing oil to one cylinder and the sight-glass on the other side to the other cylinder. These glasses are subjected to so much pressure and are so close to the engineer that when they burst, as they frequently do, injury often results to the observer, both from the glass itself and from the scalding due to the escaping heated contents.

My invention contemplates the intervention of a guard between the engineer and the sight-glass, which will protect him from injury, and the placing on the other side of the glass a reflecting-surface or mirror in such a position that the working of said glass may be as well observed by reflected light. Although, as far as the principle of my invention is concerned, this guard and mirror may be variously located, I prefer to arrange and combine them in the manner I shall now describe.

The guard C consists of a curved piece of metal or other suitable material. It is fitted before the sight-glass B, its ends bearing upon the collars of the upper and lower nuts, b, as shown, which form seats for said guard, upon which it may be turned axially to any suitable position.

Arms D are secured to the ends of the guard and extend backwardly and carry in their rear ends a pintle, E, upon which the mirror F is pivoted, so that said mirror may have an adjustment of its own, while by reason of its connection through the arms with the guard it moves also with said guard, so that their positions remain relatively unchanged. It will now be seen that the guard is between the glass and the face of the observer, and therefore protects him from injury when the glass bursts. At the same time he can observe the reflection of the glass in the mirror, and can as accurately determine the oil-feed as if he were looking directly at the sight-glass.

By reason of the adjustment of both guard and mirror the device may be arranged accurately to conform to the position of the observer, so that no matter what the position may be he will be protected; and, further, by reason of the independent adjustment of the mirror, he can arrange for the most accurate and convenient observations.

As I have said before, my invention is applicable to all devices which have sight-glasses, and I therefore do not wish to confine myself to the sight-feed lubricator I have illustrated, because the invention may be as readily applied to the sight water-glass, which is attached also to the boiler-head, and which indicates the height of the water in the boiler and other conditions necessary to be observed.

Having thus described my invention, what I claim as new, and desire to secure by Letters Patent, is—

1. A safety mirror-sight for affording the observer protection from breaking sight-glasses, comprising a guard partially enveloping the sight-glass and covering its front, and a mirror or reflecting-surface behind the glass, whereby the operation of the lubricant may be observed by reflected light, substantially as described.

2. A safety mirror-sight for affording the observer protection from breaking sight-glasses, comprising a guard-plate partially enveloping

the sight-glass, and fitted thereto so as to be capable of an axial rotation or movement, and a mirror or reflecting-surface on the other side of the sight-glass and connected with the guard-plate, whereby said guard-plate and mirror always retain their relative positions, substantially as described.

3. In combination with the axially-rotary guard-plate partially enveloping the sight-glass, the mirror or reflecting-surface on the opposite side of said sight-glass, a connection between said mirror and guard-plate, by which the two may be moved together, and a pivot-connection of the mirror, by which it may have an independent adjustment, substantially as described.

In witness whereof I have hereunto set my hand.

WINFIELD SCOTT GETCHELL.
